Fig. 6.

FIG. 1 is a top plan view of a foot control for dental equipment showing my new design, it being understood that the radiating friction ribs shown is repeated throughout the circumference of the foot control;

FIG. 2 is a side elevation thereof;

FIG. 3 is an elevation as seen from the opposite side of FIG. 2;

FIG. 4 is a bottom plan view thereof;

FIG. 5 is an enlarged section taken along the line 5-5 of FIG. 1; and

FIG. 6 is an enlarged section taken along the line 6-6 of FIG. 3.

The characteristic feature of my design resides in the low profile of the foot control as best illustrated in FIGS. 2 and 3 on the drawing.

This is a division of design application Ser. No. 13,327, filed Aug. 30, 1968.

I claim:

The ornamental design for a foot control for dental equipment, substantially as shown and described.
